UNITED STATES PATENT OFFICE.

THOMAS D. RUGGLES, OF KENT, OHIO.

OIL-CUP.

SPECIFICATION forming part of Letters Patent No. 317,580, dated May 12, 1885.

Application filed March 30, 1885. (No model.)

To all whom it may concern:

Be it known that I, THOMAS D. RUGGLES, of Kent, in the county of Portage and State of Ohio, have invented certain new and useful 5 Improvements in Oil-Cups, of which the following is a specification.

This invention relates to the peculiar construction and combination of the parts composing my oil-cup, as hereinafter fully described and claimed.

In the accompanying drawings, Figure 1 is a vertical section of my new oil-cup. Fig. 2 is a cross-section of the same. Figs. 3 and 4 are detached views of the two oil-holding cylinders.

A is a metal base, having a neck, *a*, for attaching it to the part to be lubricated. Said base is round at the ends, and has a flange, *a'*, adapted to receive two cylindrical open-ended glass vessels, B C, of peculiar shape, as hereinafter shown.

D is a metal cap-piece of the same form and construction as the base A, and has a flange for receiving the upper ends of the said cylindrical vessels. The said base and cap are secured together by two bolts, E E, which firmly hold all the parts together, and a packing-piece, F, is placed in both the base and cap, against which the ends of the glass vessels bear to insure a tight joint. The cap D has an open neck, *d*, provided with a screw-stopper, G, having a flexible gasket, *g*, to make a tight joint.

The glass vessels B C form two chambers, one of which, C, has a depression in its side, in which rests a corresponding projection on the side of the vessel B. This makes the capacity of B somewhat greater than C. The said projection also provides for bringing the opening *a*² in the neck *a* in communication with the said chamber B.

The neck *d* communicates with the interior of the chamber B by an opening, *b*.

The chamber B is for holding the oil, and the chamber C is for holding tallow.

The chamber C connects with an opening, *a*², in neck *a* by a diagonal branch opening, *c*.

A vent, *e*, is made through the wall of the neck *d* of cap D, which is covered by the flange of the stopper G, but which may be left open or opened by turning the stopper around to bring a hole through its flange in line with said vent *e*.

From the foregoing it will be seen that this is a double oil-cup, one side holding oil and the other holding tallow, and both feeding onto the same journal. The object of this is that in case the journal should heat from any cause the tallow begins to feed, thus reducing the friction and cooling the journal. The chambers B and C being of glass also enables their contents to be seen.

Having described my invention, I claim—

1. The combination, in an oil-cup, of transparent or glass chambers, the chamber C, having a longitudinal side depression, and the chamber B, having a longitudinal side projection resting in the said depression, as shown and described, and for the purpose specified.

2. In an oil-cup composed of two or more transparent or glass chambers, B C, one of which chambers projects into the side of the other, the combination therewith of a base, A, provided with neck *a* and flange *a'*, and having opening *a*², communicating with chamber B, and opening *c*, communicating with chamber C, and the cap D, having open neck *d*, provided with stopper G and vent *e*, the neck *d* communicating with chamber B, said cap and base provided with packing F, and all secured together with bolts E E, substantially as described.

THOMAS D. RUGGLES.
